UNITED STATES PATENT OFFICE.

JOHN G. ROBERTS, OF EAST ORANGE, NEW JERSEY, ASSIGNOR TO WESTERN ELECTRIC COMPANY, OF NEW YORK, N. Y., A CORPORATION OF ILLINOIS.

SUBSTATION SERVICE-METER.

1,097,366.

Specification of Letters Patent.

Patented May 19, 1914.

Application filed February 26, 1910. Serial No. 546,194.

To all whom it may concern:

Be it known that I, JOHN G. ROBERTS, a citizen of the United States, residing at East Orange, in the county of Essex and State of New Jersey, have invented a certain new and useful Improvement in Substation Service-Meters, of which the following is a full, clear, concise, and exact description.

- 10 This invention relates to service meters for telephone exchange systems of the type wherein conjoint action of the subscriber and operator is necessary to effect a registration, the subscriber not being able to signal the central office operator without actuating his plunger or other suitable manually-operable means, his service meter being thereafter solely under control of the operator, who will by the application of suitable 20 current release the service meter mechanism and advance the registering train or not, according as she has been successful or unsuccessful in establishing the desired connection.
- 25 The general object of this invention is to provide a new and improved service meter of the above type, which shall be simple in construction and efficient and reliable in operation.

- 30 To the above end the present invention provides a service meter wherein mechanical power is stored up by the subscriber in initiating a call, and the operator is provided with electromagnetic means for releasing 35 this stored up energy to advance the counting train if the connection has been successful, or to dissipate the energy and restore the service meter mechanism to normal condition without advancing the counting train 40 if the connection has been unsuccessful.

The invention will be readily apparent from the following description taken in connection with the accompanying drawing, wherein—

- 45 Figure 1 is a plan view of a service meter constructed in accordance with my invention; Fig. 2 is a side elevation thereof; Fig. 3 is a fragmentary side elevation showing the relative positions of the various operating parts when the plunger is wholly depressed; and Fig. 4 is a view similar to Fig. 3 showing the parts in the positions they assume upon release of pressure from the plunger.

The service meter shown is provided with 55 magnets 1, 2, the cores whereof pass through and are secured upon a cross bar 3. The permanent magnet 4, which is mounted upon an arm 5, preferably cast integral with the base, carries at its other end said cross bar, 60 thereby providing a support for the apparatus. The opposite ends of said cores support an armature mounting 6 carrying the tilting armature 7 which may be centrally pivoted thereon in the field of the electro- 65 magnet and adapted to swing in either direction according to the character of the current flow. The parts mentioned are of a kind well known to those skilled in the art and need not be further described. 70

The cross bar 3 supports a mounting plate 8 which forms one support for the registering train 9, while an annular extension 10 of said mounting plate forms the other support. A portion of said mounting plate extends upward from its place of support on said cross arm and forms a mounting for the usual spring-pressed plunger 11, adapted to be returned upon depression by a spiral spring 32 and held in the limit of its return 80 movement by the engagement of its pin 29 with a projection on said mounting plate. 75

The leaf spring 12, forming part of the circuit of the service meter, is anchored to the mounting plate and at its free end is pivoted to the upper extremity of a pawl 13 and to a bell crank 14, these three elements being frictionally pivoted together upon a common pivot pin 33. The said bell crank engages at its upper end the cam surface 31 90 of the plunger body and is guided into engagement therewith under the influence of spring 12 by a pin 15. The lower member of the bell crank carries a pivoted pawl 16. A spring 17 anchored to said lower member 95 rests against said pawl below its pivot point. Upon the depression of the plunger the pawl 16 rides up on a track 18 and is deflected, compressing spring 17, as shown in Fig. 3.

In order to obtain the attention of the 100 operator it is necessary that contact be made between the pawl 13 and a tooth 20 carried upon a spring 19, these two parts normally maintaining the service meter circuit open. A spring 22 is anchored at one end to the 105 leaf spring 12 and at its other to the pawl 13 below its pivot point and causes the said pawl, upon the depression of the plunger, to

engage with the tooth 20 of spring 19, the said spring being anchored upon but insulated from the mounting plate 8.

For the purpose of insuring the release 5 of pressure from the plunger to permit the spring 17 to become effective to remove the upper member of the bell crank from engagement with the cam surface 31 of said plunger, means must be provided for preventing the closure of the switch until the subscriber has released the plunger. This may be accomplished by pivoting an insulated segment 21 to the tooth 20 of spring 19 to prevent electrical contact being made 10 upon the upward movement of the pawl 13 and for a limited period after it has cleared the upper edge thereof, but adapted to permit contact to be made providing the plunger has been depressed far enough to 15 clear the protruding edge of said insulated segment and then released, the resultant retractive movement of the pawl 13 before it is locked permitting the spring 17, now compressed because of the deflection of pawl 16 20 by the track 18, to immediately be rendered active to force the upper member of the bell crank from engagement with the cam surface 31 of the plunger 11, as shown in Fig. 4.

The ratchet 24 of the registering train is 30 so located that the depression and consequent locking of the pawl 13 places the same under tension in a position such that it may be controlled by electromagnetic mechanism either to engage the ratchet and thereby advance the train or to pass by said ratchet without engaging the same. The electromagnetic mechanism is under control of the operator and may be of any suitable character provided it is capable of releasing the 35 pawl selectively. An arm 26 attached to the armature on its pivotal axis supports an insulated roller 25 which lies between extensions of the pawl 13 and leaf spring 19. In the normal position of the mechanism, 40 the downward movement of pawl 13 is limited by an insulated stop 23, the stop also holding the extensions of pawl 13 and the spring 19 away from the roller 25 to give the arm 26 a slight unrestricted movement 45 either way before engaging the said springs.

Assume current of positive polarity is applied to the line to charge a call and negative to rebate a call, and that the electromagnet in response to current of positive sign will 50 swing the armature in such manner that its end 30 engages the pole face 34. The arm 26 will thereupon cause its roller 25 to bear upon and suddenly deflect pawl 13 from engagement with tooth 20 and into engagement 55 with ratchet 24, whereupon the latent tension exerted upon said pawl by spring 12 will be free to exert itself to restore said pawl to normal, the roller bearing against the extension of the pawl and maintaining 60 the same in engagement with the ratchet 65

during the return movement, whereby the counting train is advanced one step. On the other hand, assume the call has been an unsuccessful one and the operator is to apply negative current to the line. In such event the armature will be turned oppositely, causing the roller 25 of arm 26 to bear against and deflect spring 19 laterally and disengage the same from pawl 13, the spring 12 then exerting a straight upward pull on the pawl, whereby the same is caused to pass by said ratchet without engaging the same. In either case the pin 15 guides the bell crank 14 into reengagement with the cam surface of the plunger, thereby restoring the control of the switch to the subscriber.

To guard against the possibility of the release impulse not being strong enough to move the arm 26 sufficiently to cause the pawl to clear the insulated segment 21, contacts 27, 28 are provided. These contacts are connected together and to the pawl 13. An arm 36 mounted upon but insulated from the armature and electrically connected with the electromagnet winding is arranged upon the initial movement of the armature to make contact with one or the other of these contacts 27, 28 and thus maintain the continuity of the service meter circuit until the operator removes the charging current from the line.

Having thus described my invention, I claim:

1. A service meter comprising a counting train, a manually set actuating pawl therefor, means for holding said pawl in actuated position, and electromagnetic releasing means controlling said pawl to allow it to be restored idly or to cause it to advance said counting train in such restoration.

2. In a service meter, the combination with a call register, of a spring-pressed pawl for advancing the same, an operating part for actuating said pawl, means for maintaining said pawl in its actuated position, and electromagnetic means adapted to release said pawl to be either effective or ineffective to actuate said call register.

3. A call register comprising a call indicator, an actuating device, means for manually setting said actuating device in operative relation to said call indicator, said actuating device being adapted to be restored independently of said setting means, and electromagnetic means for controlling said actuating device in such restoration to cause it to indicate a call or be restored idly according to the operation of said controlling means.

4. A service meter comprising a counting train, an actuating pawl therefor adapted to be manually moved under tension into operative relation to said counting train, holding means for said pawl, a switch operated by the actuation of said pawl, and electro-

magnetic releasing means for said pawl adapted to render the same effective or ineffective to advance said counting train.

5. A call registering device comprising a switch, means for operating said switch, a call indicator, means for registering a call thereon, a source of power for said means, and an electro responsive device controlling the restoration of said switch and source of power and to cause said registering means to be restored idly or to be restored to actuate said call register.

6. In a service meter, the combination with a counting train, of a spring-pressed pawl therefor, manual means for setting said pawl in operative position to said counting train, an electromagnet, and its armature, said armature controlling the release of said pawl, said pawl being rendered effective or allowed to be ineffective to actuate said counting train according to the direction of displacement of said armature.

7. In a service meter, the combination with a polarized electromagnet, a tilting armature therefor, a counting train, a spring-pressed pawl for advancing said counting train, manual means for moving said pawl into operative relation with respect to said counting train, means for maintaining said pawl in its operative position, and means made operative when the armature is tilted in one direction to release said pawl to advance said counting train and when the armature is tilted oppositely to release said pawl and allow the same to be ineffective to advance said counting train.

8. In a service meter, the combination with a counting train, of a spring-pressed pawl therefor, a tooth carried by said pawl, a catch, a plunger adapted to depress said pawl and cause said tooth to engage said catch and maintain said pawl under tension in operative relation to said counting train, an electromagnet, a tilting armature therefor, and means carried by said armature for releasing said pawl and determining the advance or non-advance of said counting train.

9. A service meter comprising an electromagnet, a switch, a counting train, a spring-pressed pawl for advancing said counting train, a plunger for closing said switch and moving said pawl into operative relation to said counting train, part of said switch holding said pawl in its operative position, an armature for said electromagnet adapted to release said pawl and open said switch, and means controlled by the direction of displacement of said armature adapted to render said pawl in its release effective or allow the same to be ineffective to advance said counting train.

10. A service meter having an electromagnet, a register controlling armature therefor, a switch controlling the circuit of said magnet, a register actuator controlled

by said armature, a manually-operable device adapted to close said switch and operate said actuator, and means actuated by said manually-operable device for rendering ineffective the control of said manually-operable device over said switch and said actuator.

11. In a service meter, the combination of an electromagnet, a register controlling armature therefor, a switch for controlling the circuit of said magnet, a register actuator controlled by said armature, a manually-operable device adapted to close said switch and operate said actuator, and means actuated when said switch is closed for rendering ineffective the control of said manually-operable device over said switch and said actuator.

12. In a service meter, the combination of an electromagnet, switch springs for controlling the circuit of said magnet, a register actuator controlled by said electromagnet, a plunger adapted to operate said actuator and said switch springs and thereby to close said circuit, means actuated when said circuit is closed to render ineffective the control of said plunger over said actuator and said switch springs, and means actuated upon the movement of said armature to again cause said springs and said actuator to be placed under the control of said plunger.

13. A service meter having a pawl, a plunger, an intermediate element through the agency of which said pawl is depressed by said plunger, a catch adapted to engage and maintain said pawl depressed, means for removing said intermediate member from engagement with said plunger, and means for again moving said intermediate member into engagement with said plunger upon the release of said pawl.

14. In a service meter, the combination with a counting train, a spring-pressed pawl, a pivoted bell crank, a plunger adapted to depress said pawl through the intermediation of said bell crank, a catch adapted to engage and hold said pawl in a depressed position, means for swinging said crank from engagement with said plunger when pressure is removed therefrom, means for releasing said pawl and rendering the same effective or allowing the same to be ineffective to actuate said counting train, and means actuated upon the release of said pawl for again placing the same under the control of said plunger.

15. A service meter having a spring-pressed pawl, a plunger, a frictional bell crank normally engaging said pawl and plunger and through the agency of which said pawl is depressed by said plunger, a catch adapted to maintain said pawl depressed, a compression member actuated by said plunger adapted to disengage said bell crank from said plunger and said pawl upon

the release of said plunger, and a guide adapted to cause said bell crank to again engage said plunger and pawl upon the return of said pawl to normal.

16. In a service meter, the combination with a counting train, a spring-pressed pawl adapted to advance said counting train, a plunger, an intermediate member by means of which said pawl is depressed, a catch for engaging said pawl and maintaining the same depressed, means for removing said intermediate member from engagement with said plunger when pressure is released therefrom, an electromagnet, a tilting armature therefor, releasing means for said pawl controlling by the direction of displacement of said armature the advance or non-advance of said counting train, and means operating in the return of said pawl to normal again to place the same under the control of said plunger.

17. In a service meter, the combination of a register controlling electromagnet, a circuit therefor, a switch for closing said circuit, a register actuator controlled by said electromagnet, manual means adapted to actuate said switch and said actuator, means for preventing the closure of said switch until said manual means is released, and means thereupon rendered active to remove the control of said switch and said actuator from said manual means.

18. In a service meter, the combination with an electromagnet, a circuit therefor, a switch for closing said circuit, a register actuator controlled by said electromagnet, a plunger, a bell crank engaging one terminal of said switch, and a cam surface on said plunger and through the agency of which said switch is closed and said actuator is set by said plunger, means for preventing the closure of said switch until said plunger is released, means made operative upon the release of said plunger for removing said bell crank from engagement with said plunger, and means for causing said bell crank to again engage with said plunger upon the release of said actuator and the opening of said switch.

19. In a service meter, the combination with a polarized electromagnet, a centrally pivoted armature therefor, a counting train, a spring-pressed pawl therefor, a plunger, a bell crank frictionally pivoted to the upper end of said pawl and engaging a cam surface on said plunger, a leaf spring having a catch adapted to engage a tooth upon said pawl to maintain the same depressed upon the depression of said plunger, a compression member carried by said bell crank and compressed upon the depression of said

plunger, said compression member being rendered active to remove said bell crank from engagement with said plunger upon the removal of pressure therefrom, an arm 65 carried by said armature resting between pawl and spring, and adapted when said armature is attracted to release said pawl, whereupon the said pawl in its return to normal is either effective or ineffective to 70 advance said counting train according to the direction of displacement of the armature.

20. In an electrically controlled telephone meter at a local station, the combination of 75 the counter of said meter, an actuator for the counter requiring two movements for each registration, manual means operable by the subscriber at the local station for effecting the first of said movements of the actuator, a circuit breaker in the local circuit closed by said actuator, and a device controlled from a distant station for effecting the other one of said movements.

21. In an electrically controlled telephone 85 meter, the combination with the counter, of an automatic actuator therefor, manual means for setting said actuator in position for operating the meter, a circuit maker in the local telephone circuit closed by said 90 actuator when so set, and electromagnetic means controlled from a distant station for releasing said actuator.

22. In an electrically controlled telephone 95 meter, the combination with the counter, of an automatically returning, manually advanced actuator for the counter, means for retaining the actuator in advanced position, and tripping means controlled from a distant station for releasing said actuator from 100 said retaining means and directing the return movement of said actuator relative to the counter.

23. In a telephone meter, the combination with an electrically controlled counter, of 105 actuator therefor, a push button independent of the actuator for advancing said actuator to set it in operative position, said counter being operated on the return movement of said actuator, a spring for returning the 110 push button alone to initial position, and means for preventing said push button from again advancing the actuator until the subsequent return of the actuator to initial 115 position.

In witness whereof, I, hereunto subscribe my name this 25th day of February A. D., 1910.

JOHN G. ROBERTS.
